IGNITION SYSTEM FOR INTERNAL COMBUSTION ENGINES

Lloyd H. Scott, Sidney, N. Y., assignor to Bendix Aviation Corporation, South Bend, Ind., a corporation of Delaware

Application July 22, 1936, Serial No. 91,927

7 Claims. (Cl. 123—148)

The present invention relates to an ignition system for internal combustion engines and more particularly to a dual spark ignition system in which two spark plugs in each cylinder are operated concurrently from a single source of high tension current.

Dual spark systems heretofore proposed have in general been subject to the limitations that if a single source of high tension current were employed, the arrangement was either that the voltage of such source was divided between the two spark gaps, thus necessitating a voltage source correspondingly higher than usual, or else, if a parallel arrangement were used, the current tended to flow through the gap of least resistance, and if one plug fouled, the other plug could not operate.

It is an object of the present invention to provide a dual spark ignition system for internal combustion engines which is efficient and reliable in operation and simple and economical in construction.

Another object is to provide such a device in which the full voltage of the source of high tension current is applied to each spark plug.

It is another object to provide such a device in which the total energy of the source of high tension current is divided between the spark plugs.

It is a further object to provide such a device in which fouling or shorting of one spark plug tends to increase the energy of the discharge through the other plug.

It is another object to provide such a device which incorporates means for increasing the intensity and rapidity of discharge through the spark plugs.

Further objects and advantages will be apparent from the following description taken in connection with the accompanying drawing in which:

Fig. 1 is a wiring diagram of an ignition system embodying the present invention;

Fig. 2 is a plan view of a double condenser structure particularly adapted for use in the present invention;

Fig. 3 is a side elevation thereof; and

Fig. 4 is an exploded view thereof showing the arrangement of the condenser plates and interposed sheets of dielectric material.

Referring first to Fig. 1 of the drawing, there is illustrated conventionally the primary winding 1 and secondary winding 2 of an induction coil of any suitable type of magneto. The primary 1 is connected by a lead 3 to any suitable form of breaker mechanism 4, a condenser 5 being

shunted around the breaker mechanism, and a ground switch 6 being also provided to render the device inoperative when closed. The primary circuit is completed through the ground as indicated in the usual manner. The secondary of the coil is connected by a lead 7 to the spark plugs 8 and 9 arranged in parallel, the secondary circuit being completed through the ground as usual.

According to the present invention, a pair of 10 condensers 11 and 12 are introduced in series with the spark plugs 8 and 9, the capacity of said condensers being large enough to store up a major fraction of the energy of a discharge from the secondary 2 of the ignition coil and each of 15 said condensers being large enough so that the ratio of its capacity to the inherent capacity of its series spark plug is large in order that substantially full voltage of the secondary be applied 20 across each spark plug, but being small enough so that such secondary discharge will charge the condensers to a voltage substantially above the break-down voltage of the spark plugs.

The condensers 11 and 12 are preferably though not necessarily formed as a unit as illustrated 25 in Figs. 2, 3 and 4. As best shown in Fig. 4, alternate sheets or plates 13 of conductive material such as tin foil are interspersed between similar sheets 14, being separated therefrom by sheets 15 of dielectric material such as mica. 30 A second series of conductive plates 16 are similarly arranged in cooperative relation with an additional pack of plates 14, the two packs of plates being separated by heavy sheets of dielectric material 17. Sheets 13, 14 and 16 are 35 provided with laterally extending tabs 18, 19 and 21 respectively, and the sets of tabs 18, 19 and 21 are connected to the binding posts 22, 23 and 24 respectively, the whole being preferably mold- 40 ed in a plastic dielectric material 25 to form an integral unit.

In use, the binding post 23 of the double condenser to which all the plates 14 are connected, receives the lead 7 from the secondary 2 of the induction coil, and the binding posts 22 and 24 45 connected to the plates 13 and 16 are fixed to, or connected with the spark plugs 8 and 9.

In the operation of an ignition system embodying the present invention, assuming the spark plugs 8 and 9 are in proper operative condition, a 50 discharge from the secondary of the coil, produced in the usual way by the opening of the primary circuit by the breaker 4, causes the condenser plates 14 connected to the lead 7 to become charged. This charge induces a charge of op- 55

posite polarity on the cooperative condenser plates 13 and 16 whereby a potential is built up across the gaps of the spark plugs 8 and 9 until the gaps break down and current flows through the gaps charging up the condensers. When the secondary discharge is dissipated and the voltage in the secondary lead falls, the condensers 11, 12 discharge back through the spark plugs 8 and 9, thus producing a second spark therein. The 10 operation so far described is in general the same as in case of a single ignition system having a series condenser in the secondary circuit, but it is to be noted that substantially the full voltage of the induction coil is applied equally to each 15 spark plug, while the energy of the discharge is divided equally between the plugs. If, however, the spark plug 8, for instance, should become fouled and shorted, the condenser 11 is in effect shunted around the condenser 12. The condenser 20 11 under these circumstances stores up a portion of the energy of the secondary discharge during the time that the secondary voltage is building up to the break-down voltage of the spark gap 9. When said gap breaks down, the condenser 11 discharges through the gap, supplementing the energy coming from the lead 7 and causing an intensification of the spark across the gap 9.

It is further to be understood that although the 30 invention has been here disclosed as applied to a magneto ignition system, it is also applicable to a battery ignition and distributor system with similar beneficial effects.

It will be readily seen from the above that with 35 the disclosed arrangement, a proper division of the secondary energy between the plugs 8 and 9 is always secured when the plugs are in proper condition, and if one plug should become inoperative, the discharge across the other plug is reinforced instead of being weakened.

Although but one form of the invention has been shown and described in detail, it will be understood that other forms are possible and various changes may be made in the details and 45 arrangements of the parts without departing from the spirit of the invention as defined in the claims appended hereto.

What is claimed is:

1. In a dual ignition system for internal combustion engines, a single source of high tension current, a pair of spark plugs, and means for applying substantially the full voltage of said source to each of said plugs while dividing the energy from said source between said plugs.

2. In a dual ignition system for internal combustion engines, a single source of high tension current, a pair of spark plugs, and means for applying substantially the full voltage of said source to each of said plugs, including means whereby fouling of one plug causes energy which would have produced the spark therein to reinforce the discharge through the other plug. 5

3. In a dual ignition system for internal combustion engines, a single source of high tension current, a pair of spark plugs, and means for applying substantially the full voltage of said source to each of said plugs, including means for dividing the energy from said source between the two plugs, said last means being so arranged that shorting one plug causes energy which would have produced the spark therein to reinforce the spark delivered at the other plug. 10

4. In a dual ignition system for internal combustion engines, a source of high tension current, a pair of spark plugs, a common cable for said plugs from said source, and means including an electrostatic condenser connecting each of said plugs to the common high tension cable. 15

5. In a dual ignition system for internal combustion engines, a source of high tension current, a pair of spark plugs, a common cable for said plugs from said source, and means including twin electrostatic condensers connecting said plugs in parallel with each other to said common 25 cable. 30

6. A dual ignition system for internal combustion engines including a source of alternating high tension current, a pair of spark plugs, and a connection between said source and said plugs 35 including a common cable and branches therefrom leading to the plugs, said branches including electrostatic condensers so arranged that if one plug should foul, the condenser in that branch will prevent grounding of the high tension cable 40 and function as an intensifier for the other spark plug. 45

7. A dual ignition system for internal combustion engines including a source of alternating high tension current, a pair of spark plugs, and a connection between said source and said plugs including a common cable and branches therefrom leading to the plugs, said branches including electrostatic condensers so arranged that if one plug should foul, the condenser in that branch becomes 50 in effect shunted around the other branch and operates to increase the energy and shorten the time period of discharge through the other plug. 55
